Albert R. Detrich
ATTORNEY

Patented Oct. 11, 1927.

UNITED STATES PATENT OFFICE.

FRED NESS, OF LAKE ANDES, SOUTH DAKOTA.

TOURIST'S COMBINATION BED.

Application filed March 26, 1925. Serial No. 18,520.

The invention generally relates to beds and has for its primary object to provide a simple and practical bed structure particularly adaptable for use by campers and tourists and which, for that purpose, is capable of being compacted into a relatively small bundle to facilitate its being conveniently carried on trips or stored away when its use is not desired.

- 10 In addition to its features of ready and convenient portability the invention seeks to provide a structure which is adaptable for use upon a supporting spring framing or on the ground, which, when used in the last 15 named manner and otherwise, is ground moisture, rain and water-proof, and in which provision is made for effectively clamping the bed clothing to its intended position, which feature also provides for efficient use 20 in homes and hospitals where it is found difficult to keep children and delirious patients properly confined to the covering of their beds.

With the above and other objects in view 25 that will hereinafter appear, the invention further resides in the novel details of construction, combination and arrangement of parts, all of which will be first fully described, then be particularly pointed out in 30 the appended claims, reference being had to the accompanying drawings, in which:

Figure 1 is a detail perspective view of the invention.

Figure 2 is a somewhat diagrammatic 35 cross section of the invention with the constituent parts thereof shown partially separated for purposes of clear illustration.

Figure 3 is a detail perspective view illustrating the clamping sides and end pieces.

40 Figure 4 is a detail perspective view of one of the clamping bolts.

Figure 5 is a detail perspective view illustrating how the bedding may be compacted to facilitate the transportation thereof.

45 In the drawings, in which like numerals of reference indicate like parts in all of the figures, 1 serves to indicate the mattress which, while it may be of any type commonly used in making up bedding, is preferably of a light weight type such as is desirable for camping purposes and which may be readily rolled up into the compact condition indicated in Figure 5 of the drawing. 50 In the drawing, the numeral 2 indicates the usual mattress covering sheet, which may be tucked in downwardly around the edges

of the mattress or not, as desired, 3 the covering sheet and 4 a blanket, or other covering, the use of which is, of course, optional according to the conditions of the weather. 60 Thus far, I have described bedding material which is commonly used for all purposes and the usual arrangement of which is well understood.

In carrying out the principles of my invention, I provide a lower mattress protecting sheeting 5, preferably of rubberized fabric or other suitable moisture repelling material, which is adapted to be folded up over the edges of the mattress at the sides and bottom end thereof in the manner indicated in Figures 2 and 3 of the drawings, and an upper top protecting sheet 6 constructed of similar material and adapted to have the edges thereof overlap the upturned edges of 75 the lower sheet 5.

For tightly securing the bedding to the desired positions indicated in Figures 2 and 3 of the drawings I provide upper and lower opposed sides clamping pieces 7 preferably 80 constructed of metal to include down-turned clamping or clamping edges 8, or in other words, being of inverted U shape in cross section so as to present the edges 8 of the U, in clamping relation against the bedding. 85 The sides clamping pieces 7 are preferably constructed in two or more sections, as shown in Figure 1 of the drawings, and are apertured as at 9 for purposes later to be described.

Foot end clamping pieces 10 are also provided, constructed similar to the side pieces 7 with the exception of not being constructed in sections, and are suitably apertured as at 11. At the meeting ends of the respective 95 side and end pieces 7 and 10 they are suitably cut out and flattened as at 12, to facilitate proper cooperation thereof at the lower corners of the bed.

The apertures 9 and 11 with which the 100 side and foot end pieces 7 and 10 are equipped serve to facilitate the application of clamping bolts 13, a sufficient number of which are used to provide for the desired clamping of the said pieces to position. 105 Each bolt 13 is constructed to include a lower double squared head 14 the upper squared portion of which acts as an abutment and engages the uppermost face of the respective bottom clamping pieces 7 or 10, 110 while the lower squared portion serves to prevent rotation by passing through the

apertures 9 which in the case of said lower pieces 7 or 10 are squared for that purpose, a sharpened upper end 15 for facilitating the desired piercing of the mattress when being 5 moved to cooperative position, and threaded ends for receiving the limiting or upper clamping heads 16 for engaging the top surface of the mattress and providing suitable abutment limiting the final securing, and the 10 final upper end lower securing heads 17 adapted to oppose the top and bottom surfaces of the pieces 7 and 10 for securing them to clamping condition in the manner illustrated in Figures 1, 2 and 4 of the 15 drawing. The securing heads 17, especially the upper ones thereof, are readily removable by the user of the bed or an attendant, and by reason of providing at least one set of side clamping pieces in sections it is possible to readily remove the uppermost section of one of the sides to facilitate the turning down of the bed covering so that the occupant can readily slip into the same when 20 after again applying the removed piece and 25 securing the member 17 the bed clothing will be clamped to the desired position against inadvertent or undesired removal.

It will be obvious that a bed structure constructed as herein described is very practical 30 for camping purposes in that it will effectively repel moisture from above and below the bed, and will efficiently ensure against inadvertent or undesired displacement of the bed clothing rendering the same particularly 35 adaptable for use in camping or for use in homes or hospitals where it is a common thing for children and delirious patients to repeatedly uncover themselves with the danger, in the first instance, of the child 40 falling from the bed or catching cold, and in the latter instance the danger to the patient, either through physical injury brought on during a roaming about in a delirious condition or a relapse suffered from exposure. It 45 will also be readily apparent that the bed structure illustrated, by reason of the manner of constructing the same is readily adaptable for use directly upon the ground in camping, or in a home or hospital upon a suitable 50 spring equipped supporting frame.

The provision of the sectional sides clamping pieces 7 also facilitates the rolling up of the complete bedding into a compact roll in the manner illustrated in Figure 6 of the 55 drawing, it being understood that when this is accomplished, the said pieces will be collapsed and inserted into the inner portion of the roll.

By reason of extending the edges of the 60 top protecting sheet 6 over the upturned edges of the lower sheet 5, drainage of any water, due to rain or dew when the device is used out of doors, into communication with the bed clothing proper is guarded against. 65 To further facilitate the transportation of

the invention when compacted, one of the end clamping pieces 10, if desired, may be equipped with a pair of cross slots 18 through which may be projected the ends of a collapsible handle strap 19, suitable enlargements 20 being connected to each said end after its insertion through the respective slot to prevent further removal thereof. When thus equipped and applied as indicated in Figure 6 of the drawing a suitable handle 70 for the compacted bedding is provided.

From the foregoing description taken in connection with the accompanying drawing, it is thought the complete construction, manner of operation and advantages of my invention will be readily apparent to those familiar with the use of such equipment.

What I claim is:

1. The combination with a mattress and the usual covering therefor, of side and foot 85 end clamp pieces, and bolts adapted to pass through the clamp pieces and the mattress and parts of the covering for clamping said pieces to position for holding the covering to the desired position upon the mattress, said bolts having pointed top heads for 90 piercing the mattress.

2. The combination with a mattress and the usual covering therefor, of a lower protective sheeting adapted to be folded up over 95 the sides and foot of the mattress, an upper protective sheeting, upper and lower opposed side and foot end clamp pieces, and means for clamping the said pieces to position for holding the covering and the upper and lower sheetings to the desired position upon the mattress.

3. The combination with a mattress and the usual covering therefor, of a lower protective sheeting adapted to be folded up over 105 the sides and foot of the mattress, an upper protective sheeting, upper and lower opposed side and foot end clamp pieces, and means for clamping the side pieces to position for holding the covering and the upper and lower sheetings to the desired position upon the mattress, the said upper sheeting being of a width for lapping over the up-folded edges of the lower sheeting to protect against water drainage.

4. The combination with a mattress and the usual covering therefor, of a lower protective sheeting adapted to be folded up over the sides and foot of the mattress, an upper protective sheeting, side and foot and clamp 110 pieces, and bolts for clamping the said pieces to position for holding the covering and the upper and lower sheetings to the desired position upon the mattress, said bolts being adapted to pass through the mattress, the up-folded over edges of the lower sheeting, and the clamp pieces.

5. The combination with a mattress and the usual covering therefor, of a lower protective sheeting adapted to be folded up over 120

the sides and foot of the mattress, an upper protective sheeting, side and foot end clamp pieces, and bolts for clamping the said pieces to position for holding the covering and the 5 upper and lower sheetings to the desired position upon the mattress, said bolts being adapted to pass through the mattress, the up-folded over edges of the lower sheeting, and the clamp pieces, at least one of the said side 10 pieces having at least one removable section for the purpose specified.

6. The combination with a mattress and the usual covering therefor, of a lower protective sheeting adapted to be folded up over 15 the sides and foot of the mattress, an upper protective sheeting, opposed upper and lower side and foot end clamp pieces, bolts for clamping the said pieces to position for holding the covering and the upper and lower 20 sheetings to the desired position upon the mattress, said bolts being adapted to pass through the mattress, the up-folded over edges of the lower sheeting and the clamp pieces, and each having a pair of securing 25 heads, one for engaging the top surface of the mattress and one for engaging the top surface presented by the respective clamp piece through which the bolt passes.

7. The combination with a mattress and 30 the usual covering therefor, of opposed upper and lower side and foot end clamp pieces, and means for clamping the said pieces to po-

sition for holding the covering to the desired position upon the mattress, one of the opposed end clamp pieces having a collapsible 35 strap handle to facilitate carrying of the whole bed structure combination when compacted for that purpose.

8. The combination with a mattress and the usual covering therefor, of a lower protective sheeting adapted to be folded up over 40 the sides and foot of the mattress, an upper protective sheeting, opposed upper and lower side and foot end clamp pieces, bolts for clamping the said pieces to position for holding the covering and the upper and lower sheetings to the desired position upon the mattress, said bolts being adapted to pass through the mattress, the up-folded over 45 edges of the lower sheeting and the clamp pieces, each having a pair of securing heads, one for engaging the top surface of the mattress and one for engaging the top surface presented by the respective clamp piece through which the bolt passes, a double 50 squared portion abutting the top surfaces of the lower clamp pieces and having a non-circular portion for passing through said lower clamp pieces for preventing rotation, and a lower securing head adapted to abut 55 the lower surfaces of the said lower clamp pieces substantially as and for the purposes described.

FRED NESS.
